[57] CLAIM

The ornamental design for a shin pad for a ladder, as shown and described.

DESCRIPTION

FIG. 1 is an environmental perspective view of a shin pad for a ladder showing our new design;

FIG. 2 is a rear elevational view thereof;

FIG. 3 is a front elevational view thereof;

FIG. 4 is a left side elevational view with the right side being a mirror image thereof; and,

FIG. 5 is a top view thereof with the bottom view being a mirror image thereof.

The broken line showing of a ladder is for illustrative purposes only and forms no part of the claimed design.
